**GAS DISCHARGE TUBE HAVING A PASCHEN
VALUE LESS THAN THE PASCHEN VALUE
OF GAS AND AIR**

Hans Mungard, Langesø, Denmark, assignor to Danfoss
A/S, Nordborg, Denmark, a company of Denmark
Filed Aug. 31, 1964, Ser. No. 393,163
5 Claims. (Cl. 250—83.6)

This invention relates generally to radiation detectors and more particularly to gas-filled detector tubes which operate according to Geiger-Muller principles.

Radiation detectors, in the form of gas-filled detector tubes, in which an ionizable gas is contained in a radiation pervious chamber containing the gas and in which electrodes are disposed and to which is applied a specific or selected working voltage are well known. In these devices the radiation ionizes the gas in the tube such that electron flow results and the tube is rendered conductive or fires. Such tubes are used for detecting electromagnetic radiation having wave lengths in the region of the electromagnetic spectrum comprising ultraviolet radiation, for example, in automatic controls for sensing a flame in heaters and in fire alarms.

The known devices or tubes, however, do not always operate accurately since at times they are rendered conductive and indicate the presence of radiation when none exists. This may result after a period of time when the tube has been installed or when the normal applied voltage is applied thereto even in the absence of radiation. This kind of improper operation may result, for example, in the actuation of a fire alarm when there is actually no fire or in heaters, having such devices, when the flame is out and the device can continue the operation of an oil pump and the delivery of oil to a burner even when the flame is out.

A principal object of the present invention is to provide a gas-filled radiation detector tube, for detecting electromagnetic radiation in the region of the spectrum comprising ultraviolet radiation, which is substantially, absolutely reliable in its operation.

A feature of the detector tubes according to the invention is a tube construction in which the minimum value of a Paschen curve of the gas is lower than the minimum value of either a Paschen curve of air or of a gas-air mixture. It is known that microscopically fine leaks, exist in tubes sometimes allowing the entry of air thereby resulting in a Paschen curve change which can result in misoperation of the known tubes. If initially the detector tubes are operated on an ignition or firing point on the descending or negative branch of the Paschen curve, then the ignition or firing voltage level is lowered by the entry of air. Thus, self-ignition can occur with normal operating voltage applied to the tube.

According to the invention, the selection of the relative minimum values of the Paschen curves of the gas and the air of gas-air mixture is such that the gas Paschen curve minimum value is below the minimum value of the other curves and thereby ensures safe operation. Thus by selecting the working voltage, the type of gas and the product of the gas pressure and the distance between the electrodes resulting in such a Paschen curve the device according to the invention will detect ultraviolet radiation as desired and will not fire in the absence of the presence of radiation.

Another feature according to the invention is a gas-filled detector tube construction in which the original datum or point of ignition is chosen to lie on the rising or positive branch of the Paschen curve of the gas and the gas-air mixture curve.

Other features and advantages of the radiation detection tube in accordance with the present invention will be

better understood as described in the following specification and appended claims, in conjunction with the following drawing in which:

FIG. 1 is a diagram of Paschen curves for illustrating the principles of the invention; and

FIG. 2 is a diagrammatic illustration of a detector tube according to the invention.

Those skilled in the art know that Paschen's Law states that the sparking potential between two parallel-plate electrodes in a gas is proportional to the product of gas pressure and electrode spacing. According to the diagram or plot in FIG. 1, the ordinate $U_z (v)$ designates the applied voltage values and the abscissa in the diagram is representative of the product, $p \times d$, of the air pressure p in the interior of an ultraviolet detector tube and the distance d between the electrodes. In the curves illustrated, the curve G is a Paschen curve of a substantially pure gas and the curve L is the Paschen curve for air. These Paschen curves are known for certain gases and may be found in standard treatises.

From the plot or diagram in FIG. 1 it can be seen that the self-ignition voltage of the gas can change very rapidly if it lies on the negative branch of the gas curve in view of the rapidly descending curve of the product $p \times d$ increases and therefore it can easily fall below a normally applied voltage if the gas pressure in the interior of the tube is increased by the addition of air, for example, thereby resulting in an increase in the product $p \times d$ and firing of the tube in the absence of ionizing radiation. If gas-filled tubes worked properly and were absolutely airtight, a detector tube might be constructed with an ignition point chosen far up on the descending or negative branch of the Paschen curve of the gas and the working or applied voltage could be at a level between this point and the minimum value of the curve. However, as indicated heretofore, the entrance of air does result and the tubes constructed in this manner will misoperate.

The diagram on FIG. 1 illustrates two examples of constructions which are used according to the invention for constructing detector tubes. According to the invention the gas Paschen curve G has a minimum value below the value of the air Paschen curve L and self-ignition voltage P_1 is selected relative to an applied voltage U_{a1} and the product of the gas pressure and the distance between the electrodes. In the event that in such a construction air enters the tube the Paschen curve, the curve G of the gas, changes gradually into the Paschen curve values of air so that the resulting mixture curve is illustrated as a curve U_1 which is representative of the transition between a relatively pure gas to a gas-air mixture. The working voltage or applied voltage U_{a1} is below the minimum value of the curve G so that an intersection of the Paschen curve with the working voltage cannot occur and the tube will not fire unless radiation is sensed and the gas ionized. As may be seen from the graph or diagram, the applied voltage U_{a1} may even be raised a little to a higher value since the curve U_1 is not a descending curve but a rising curve which, at first, is substantially a flat horizontal curve and then rises gradually. Thus by constructing a tube in which the gas has a Paschen curve minimum value below the minimum value of the Paschen curve of air, as a function of the product of the gas pressure and the distance between the electrodes selected for such a tube and resulting in such a curve if a working voltage is applied as above the result is a tube that will detect the presence of ultraviolet radiation and still will not fire or be rendered conductive in the absence thereof.

According to the invention, another construction is possible in which the firing or ignition voltage point P_2 is chosen to lie on the rising or positive branch of the Paschen curve of the gas. In the event that the tube has a minor leak, the entering air will cause the gas Paschen

curve G to assume values illustrated by the curve U_2 . In this construction, the applied voltage U_{a2} may be selected and applied at a value far above the minimum value of the Paschen curve G. The rapidly rising curve U_2 will preclude self-ignition in the absence of ionization resulting from detection or sensing of ionizing radiation.

A detector tube constructed according to the invention is illustrated in FIG. 2, in which the tube comprises means which may be, for example, an envelope 1 which is pervious to ultraviolet radiation or at least has a portion thereof which is a "window" and pervious to this radiation defining a gas chamber 3 in which is contained an ionizable gas. The tube comprises two parallel spaced electrodes 4 and 5 having pins 6 and 7 connected thereto respectively for connecting the electrodes to a power voltage source as illustrated by which the selected operating voltage is applied. Upon the incidence of ultraviolet radiation, on the gas chamber 3 the gas is ionized and the tube will ignite when the ignition point is reached as above described.

While preferred embodiments of the invention have been shown and described, it will be understood that many modifications and changes can be made within the true spirit and scope of the invention.

What I claim and desire to secure by Letters Patent is:

1. A gas-filled detector tube for detecting electromagnetic radiation having wave lengths in the region of the electromagnetic spectrum comprising ultraviolet radiation, said tube comprising, means defining a gas chamber having at least a portion pervious to electromagnetic radiation having wave lengths comprising ultraviolet radiation, an ionizable gas in said chamber ionizable by said radiation, two spaced, parallel electrodes internally of said chamber, means connected to said electrodes for receiving a selected voltage for application to said electrodes in operation for firing said tube when said radiation ionizes said gas, the product of the pressure of said gas and the distance between electrodes of said tube being selected and represented by a Paschen curve having a minimum value less than the minimum value represented by a Paschen curve of a mixture of said gas and air, and said voltage having a selected value relative to level of the minimum value of said gas Paschen curve.

2. A gas-filled detector tube according to claim 1, in which said voltage has a value below the minimum value of the Paschen curve of said gas.

3. A gas-filled detector tube according to claim 1, in which said voltage has a value above the minimum value of said Paschen curve, and in which the point of ignition is on a rising portion of said gas Paschen curve.

4. A gas-filled detector tube for detecting electromagnetic radiation having wave lengths in the region of the electromagnetic spectrum comprising ultraviolet radiation, said tube comprising, means defining a gas chamber having at least a portion pervious to electromagnetic radiation having wave lengths comprising ultraviolet radiation, an ionizable gas in said chamber ionizable by said radiation, two spaced, parallel electrodes internally of said chamber, means connected to said electrodes for receiving a selected voltage for application to said electrodes in operation for firing said tube only when said radiation ionizes said gas, the product of the pressure of said gas and the distance between electrodes of said tube being selected and represented by a Paschen curve of a mixture of air and said gas having a minimum value above the level of the selected voltage.

5. A gas-filled detector tube for detecting electromagnetic radiation having wave lengths in the region of the electromagnetic spectrum comprising ultraviolet radiation, said tube comprising, means defining a gas chamber having at least a portion pervious to electromagnetic radiation having wave lengths comprising ultraviolet radiation, an ionizable gas in said chamber ionizable by said radiation, two spaced, parallel electrodes internally of said chamber, means connected to said electrodes for applying a selected voltage to said electrodes in operation for firing said tube when said radiation ionizes said gas to a given level of ionization, the product of the pressure of said gas and the distance between electrodes of said tube being selected and represented by a Paschen curve having a minimum value less than the minimum value represented by a Paschen curve of a mixture of said gas and air, and said voltage having a selected value relative to the minimum value of said gas Paschen curve.
